Primary Examiner — Karen E Eldridge Powers(74) *Attorney, Agent, or Firm* — Gottlieb, Rackman & Reisman, P.C.(57) **CLAIM**

The ornamental design for a hat, as shown and described.

DESCRIPTION

FIG. 1 is a perspective view of the hat showing my new design;

FIG. 2 is a top plan view thereof;

FIG. 3 is a bottom plan view thereof; and,

FIG. 4 is a front elevational view thereof.

The finely-incremented broken lines shown on the edge of the brim of the hat are stitching and form a part of the claimed design. The remaining broken lines in the drawings illustrate unclaimed features.
